BATH BRUSH

Edna Mae Klenk, Coral Gables, Fla.
(8800 SW. 8th St., 905G, Miami, Fla. 32144)

Filed Jan. 25, 1966, Ser. No. 760

Term of patent 14 years

(Cl. D9—2)

The characteristic features of my design for the bath brush disclosed reside in the handle portions having the configuration as shown in association with the bristle unit thereof.

I claim:

The ornamental design for a bath brush, as shown and described.
